HOLDER FOR COMPRESSIBLE PASTE-
DISPENSING OR LIKE TUBESJack E. Palmer, Barberton, Ohio, assignor of two-
fifths to Lillian Helper, Akron, Ohio

Application April 16, 1948, Serial No. 21,504

6 Claims. (Cl. 222—101)

1

This invention relates to a holder for compressible tubes for dispensing tooth paste or the like.

One object of the invention is to provide a device of the character described including a casing in which a collapsible tube of paste is adapted to be received in inverted position, and improved means for progressively applying pressure from the inverted bottom end of the tube to squeeze the paste from the tube orifice presented at the bottom of the casing, the pressure-applying means being movable away from pressure-applying position to facilitate ready passage of the tubes into and out of the casing.

Another object of the invention is to provide a device of the character described which may be manufactured at a minimum of cost as compared with prior art devices.

These and other objects of the invention will be manifest from the following brief description and the accompanying drawings.

Of the accompanying drawings:

Figure 1 is a vertical transverse cross-section through a tooth paste tube holder, embodying the features of the invention.

Figure 2 is a cross-section, taken substantially on the line 2—2 of Figure 1.

Referring to the drawings, the numeral 10 designates a box-like holder or casing having a back wall 11 against which a collapsible tube of tooth paste 12 may be backed in inverted position as shown, the tube being supported by engagement of a nozzle end of the same with a bottom wall 13 of the casing. The wall 13 is provided with an orifice 14 through which the dispensing nozzle 15 of the tube projects. Rotatably received through vertically extending elongated slots 16, 16, in laterally spaced side walls 17, 17 of the casing, may be a shaft 18 on which is rotatably mounted a roller 19, of rubber or other suitable material to be engageable with the tube. The slots are in parallelism with the back wall 11, and the radius of the roller approximates the distance from the vertical center of the slots to the inner face of said back wall, less at least the thickness of the tube in a flattened or collapsed condition.

The roller 19 is narrower than the space between the two side walls 17 to provide substantial spaces 20 and 21 on the shaft 18, between ends of the roller and the adjacent side walls 17. Extended between each shaft portion 18a, 18a in said spaces and the bottom wall 13 may be flexible elements 22, 22, of wire, cord, chain, or the like, adapted to be wound on said shaft portions as the shaft is rotated in counter-clockwise direction as viewed in Figure 1. The shaft is so rotated as

by manual operation of a knob 23 fixed on one end of the same projecting outwardly of the casing 10. That is, the flexible elements are arranged to be maintained in taut condition, as the knob 23 is turned in said counter-clockwise direction, by opposing pressure of roller 19 against an expanded or filled part of the tube 12, and continued rotation of the roller in this manner, that is with forced downward movement of shaft 18, from a position adjacent the top of the casing will progressively flatten or collapse the tube from the inverted bottom end thereof toward the downwardly presented nozzle end thereof, to squeeze paste from the nozzle opening as desired. Although the roller 19 works most effectively when rotatably mounted on shaft 18, it is self-evident that if roller 19 were fixed on said shaft any differential between the speed at which element 22 is wound and the peripheral speed of the roller 19 would be compensated for by sliding movement of the roller on the tube, as distinguished from rolling movement of the roller, as force is applied to knob 23 to turn the shaft.

For adjustably attaching the flexible elements 22 to the casing as described, they may be attached to the inner ends of screws 24, 24 threaded through nuts 25, 25 which are suitably anchored to the bottom wall 13. Thus the screws 24 are vertically adjustable from the exterior of the casing, to set both elements 22 at uniform tension.

An opening is provided in the top of the casing 10 for inserting therein filled tubes 12, or for removing collapsed or empty tubes from the same, the opening being normally closed as by means of a hinged closure 26. To facilitate such insertion or removal of the tubes, the slots 16 in the side walls are extended at 16a, substantially at right angles to the vertical portions of the slots in direction forwardly of the back wall 11, whereby by unwinding the elements 22 the roller 19 may be moved forwardly a distance sufficient to permit passage of a full tube between the roller and said back wall.

A cap 27 is hinged on the outer face of bottom wall 13, in position to be engageable with the projecting end of nozzle 15, to close the opening of the same when paste is not being dispensed.

In use of the holder 10, described above as a tooth paste dispenser, it is adapted to be mounted on a bathroom wall in the relative position shown in the drawing, as by means of screws received through spaced keyhole slots 11a in the back wall 11. A tube of tooth paste 12 is maintained against the back wall 11 of the holder by engagement of the roller 19 therewith (see Figure 2), and

when it is desired to dispense a small quantity of paste from the nozzle 15 onto a toothbrush, it is only necessary to turn knob 23 a fraction of a revolution in clockwise direction as shown in Figure 1, to wind the elements 22 on the shaft portions 18a, and thereby to urge the roller 19 downwardly against the full part of the tube. When all of the paste has been dispensed in this manner, the roller 19 may be moved upwardly and outwardly along the slot extensions (see chain-dotted lines in Figure 1) 16a by rotating the knob 23 to unwind the flexible elements 22, thereby to permit replacement of the flattened tube 12 with a full one, through the top of the hole.

Modifications of the invention may be resorted to without departing from the spirit thereof or the scope of the appended claims.

What is claimed is:

1. A holder for a compressible tooth paste or like dispensing tube, comprising a support, a backing member, means for supporting the tube on said support backed against the member with the outlet of the tube at one end of the support, spaced sides angularly of said backing member and having elongated slots substantially parallel to the backing member, a shaft having ends rotatably received through said slots, a roller on said shaft, the periphery of said roller being generally at a radius substantially equal to the distance from the center of said slots to said backing member less the thickness of the tube when compressed, one or more spaced flexible elements connected from said end of said support to said shaft, means for rotating said shaft to wind said flexible element or elements on the shaft against tension thereon applied by opposing pressure on a filled part of said tube being compressed by said roller as it is urged toward said end of the support by the winding action, said opposing pressure on the tube progressively collapsing the same to dispense the paste through the tube outlet.

2. A holder for a compressible tooth paste or like dispensing tube, comprising a support, a backing member, means for supporting the tube on said support backed against the member with the outlet of the tube at one end of the support, spaced sides angularly of said backing member and having elongated slots substantially parallel to the backing member, a shaft having ends rotatably received through said slots, a roller rotatably mounted on said shaft, the periphery of said roller being generally of a radius substantially equal to the distance from the center of said slots to said backing member less the thickness of the tube when compressed, said roller being narrower than the width between said side members to provide winding space on said shaft between the ends of the roller and the side members, spaced flexible elements connected from said end of said support to said shaft in said winding spaces, means for rotating said shaft to wind said flexible elements on the shaft against tension thereon applied by opposing pressure on a filled part of said tube being compressed by said roller as it is urged toward said end of the support by the winding action, said opposing pressure on the tube progressively collapsing the same to dispense the paste through the tube outlet.

3. A holder for a compressible tooth paste or

like dispensing tube, comprising a support, a backing member, means for supporting the tube on said support backed against the member with the outlet of the tube at one end of the support, spaced sides angularly of said backing member and having elongated slots substantially parallel to the backing member, a shaft having ends rotatably received through said slots, a roller on said shaft, the periphery of said roller being generally of a radius substantially equal to the distance from the center of said slots to said backing member less the thickness of the tube when compressed, said roller being narrower than the width between said side members to provide winding space on said shaft between the ends of the roller and the side members, spaced flexible elements connected from said end of said support to said shaft in said winding spaces, means for rotating said shaft to wind said flexible elements on the shaft against tension thereon applied by opposing pressure on a filled part of said tube being compressed by said roller as it is urged toward said end of the support by the winding action, said opposing pressure on the tube progressively collapsing the same to dispense the paste through the tube outlet.

4. A holder for a compressible tooth paste or like dispensing tube, comprising a casing having an apertured bottom member for receiving the nozzle of the tube to project outwardly of the casing, a vertical backing member against which the tube is to be supported, and opposite side members having therein oppositely disposed elongated slots extending vertically, a roller extending between said side members and having spindles rotatably received through said slots, the radius of said roller being substantially equal to the distance from the center of the vertical slots to the backing member less the thickness of the tube when compressed, said roller being narrower than the width between said side members to provide winding space on said spindles between the ends of the roller and the side members, spaced flexible elements connected between said bottom member and said spindles in the winding spaces thereof, manually operable means for rotating said roller to wind said flexible elements on the spindles against tension thereon applied by opposing pressure on a filled part of said tube being compressed by said roller as it is urged downwardly by the winding action, said opposing pressure on the tube progressively collapsing the same to dispense the paste through the nozzle.

5. A holder for a compressible paste-dispensing tube as set forth in claim 1, said slots being relieved in direction outwardly of said backing member at the other end of said support, for moving said shaft and roller outwardly to permit passage of a tube into or out of the holder.

6. A holder for a compressible paste-dispensing tube as set forth in claim 4, said casing having an opening in the top thereof, said slots being relieved in direction outwardly of said backing member at the top of said casing, for moving said shaft and roller outwardly and thereby permit passage of a tube into or out of said casing through said top opening.

JACK E. PALMER.
